UNITED STATES PATENT OFFICE.

SAMUEL S. YAGER AND CHARLES B. HEBBARD, OF JOPLIN, MISSOURI, SAID HEBBARD
ASSIGNOR TO SAID YAGER.

POCKET SAFETY DEVICE.

1,149,242.

Specification of Letters Patent.

Patented Aug. 10, 1915.

Application filed October 10, 1914. Serial No. 866,176.

To all whom it may concern:

Be it known that we, SAMUEL S. YAGER and CHARLES B. HEBBARD, citizens of the United States, residing at Joplin, in the county of Jasper and State of Missouri, have invented certain new and useful Improvements in Pocket Safety Devices, of which the following is a specification.

The present invention relates to improvements in safety devices for retaining the pockets closed, particularly the side pockets of trousers, while not necessarily restricted to this use.

An important object of the invention is to provide a device of the above mentioned character, so constructed that when the same is holding the pocket closed, the parts thereof will fold up flat providing a structure conforming to the curvature of the hip, thus not perceptibly impairing the appearance of the trousers or inconveniencing the wearer.

A further object of the invention is to provide means for operating the device to partly or wholly open the pocket, such means being adapted to be operated by one hand from the exterior of the pocket.

A further object of the invention is to provide a device of the above mentioned character, which is simple in construction, inexpensive to manufacture, and highly convenient in use.

Other objects and advantages of the invention will be apparent during the course of the following description.

In the accompanying drawings forming a part of this specification and in which like numerals are employed to designate like parts throughout the same, Figure 1 is a longitudinal sectional view through the side pocket of a trouser showing our device, in elevation, applied thereto, Fig. 2 is an edge elevation of the device removed and open, Fig. 3 is a similar view with the same closed, Fig. 4 is a side elevation of the device, and, Fig. 5 is an elevation of the opposite side thereof.

In the drawings, wherein for the purpose of illustration is shown a preferred embodiment of our invention, the numeral 10 designates an outer longitudinally curved leaf spring, preferably formed of spring tempered steel. This spring is preferably arranged upon the inner side of portion 11 of the pocket, preferably between the folded material of the same. The portion 11 is provided at the ends of the pocket with open-

ings, to allow for the passage of the ends of the spring 10. This spring is provided near its ends with openings or notches 12', receiving wrappings of thread, stitched through the material of the trousers. Preferably in this manner, the spring 10 is retained in place.

The numeral 12 designates a co-acting control member, preferably formed in three or more sections 13 and 14, hinged together at 15 15'. The end sections 13 are hinged to the ends of the curved spring 10, as shown at 16. The sections 13 and 14 are preferably formed of spring tempered steel. The control member 12 is arranged inwardly of the inner side 13' of the pocket, and is preferably covered by a lining 14'. By being formed in three or more sections, when the control member 12 is moved to the closed position, such control member will lie flat upon the spring 10 and the entire device will conform substantially in curvature to the hip, thus taking up the minimum space and not perceptibly impairing the appearance of the trousers or inconveniencing the wearer.

The principal difficulty heretofore encountered in the use of devices of this character has been in operating them to open the pocket. Such devices ordinarily require the employment of the two hands for their operation, and then it is often difficult. To overcome this disadvantage, we secure one end 17 of a supplemental spring 18, to the exterior surface of the curved spring 10, the opposite end of the spring 18 slidably engaging the spring 10. Attached to the spring 18 between the ends thereof is an inwardly extending pin 19, passing through an aperture 19' within the spring 10, and adapted to engage with the section 14 adjacent the upper hinge 15, when spring 18 is moved inwardly by pressure upon the exterior thereof. When this spring is moved inwardly, pin 19 moves the upper end of section 14 inwardly, whereby the lower end of upper section 13 is swung inwardly past dead center, the same automatically springing to the open position while the lower end of the section 14 and the lower section 13 remain in the closed position. The opening operation is then completed by inserting a hand in the partly open pocket.

It is to be understood that the form of our invention herewith shown and described is to be taken as a preferred example of the

same, and that various changes in the shape, size, and arrangement of parts may be resorted to without departing from the spirit of the invention or the scope of the subjoined 5 claims.

Having thus described our invention, we claim:—

- 10 1. A safety pocket device, comprising a curved spring, a control member pivotally connected with the ends of the curved spring, and a supplemental spring secured to the curved spring and carrying a lateral extension adapted to contact with the control member.
- 15 2. A safety pocket device, comprising a curved spring, a control member pivotally connected with the ends of the curved spring and formed in a plurality of pivoted sections, and a device connected with the curved 20 spring and movable laterally with relation thereto and having a rigid lateral extension

adapted to contact with one of the sections of the control member to move it away from the curved spring.

3. A safety pocket device, comprising a curved spring provided between its ends with an aperture, a control member pivotally connected therewith and formed in a plurality of hinged sections, and a supplemental spring having one end thereof secured to the curved spring with its opposite end slidably engaging therewith and carrying a laterally extending pin passing through the aperture of the curved spring to contact with a section of the control member.

35 In testimony whereof we affix our signatures in presence of two witnesses.

SAMUEL S. YAGER.
CHARLES B. HEBBARD.
